UNITED STATES PATENT OFFICE.

ERNEST H. FOSTER, OF NEW YORK, N. Y.

SUPERHEATER.

1,106,026.

Specification of Letters Patent.

Patented Aug. 4, 1914.

Application filed November 30, 1912. Serial No. 734,420.

To all whom it may concern:

Be it known that I, ERNEST H. FOSTER, a citizen of the United States, residing at New York, county of Richmond, and State of New York, have invented certain new and useful Improvements in Superheaters, of which the following is a full, clear, and exact description.

The object of my present application for patent is an improvement in connection with water-tube boilers of the so-called "vertical tube" form, of which the Sterling boiler may be regarded as typical, and resides in a novel combination of a superheater with such a boiler, and in the details of construction accessory thereto. In arranging a superheater in connection with a boiler of the type mentioned, while it is desirable to utilize the boiler heating chamber of the setting as the location of the superheater, in order that the latter may receive heat directly from the gases which also heat the boiler, the precise location of the superheater is, largely governed by the degree of superheat required so that it has long been customary to place the device in one or another of the several passes or paths followed by the hot gases. In all cases however some means of support for the superheater must be provided, and this presents practical difficulties by reason of the width of the boiler setting and the destructive effect of the hot gases on any supports which may be inserted for the purpose. Furthermore, supports within the setting would have nothing to rest on but the heating surface of the boiler, an arrangement which is seriously inconvenient because of the increased difficulty of removing boiler tubes when necessary for purposes of repair, and because of the necessity of strengthening parts which are not intended to carry weights.

My present invention provides a plan whereby the entire superheater is located within the boiler heating chamber in a position most favorable to obtaining a high degree of superheat, and under conditions which insure the most effective utilization of the superheater surface, while not interfering with the direct action of the hot gases upon, and their free passage over the boiler tubes.

According to my improvement a superheater, of the ordinary type or form known as the U-tube, that is a plurality of tubes bent in the form of the letter U, and con-

nected at their ends to parallel heaters, is placed between the first and second or middle bends of vertical tubes. The headers extend across the heating chamber horizontally, and are supported by hangers, preferably embedded in the setting or brick walls of the structure that houses the boiler, and suspended from or supported by the horizontal transverse steel beams that in 60 boilers of this class are employed as the supports for the boiler drums. The bent tubes connecting these headers extend upward, substantially parallel with the boiler tubes, thus occupying the upper portion of the 70 space between the first and middle bends. In order, however, that the hot gases may pass over the banks of tubes in uninterrupted series from end to end, a condition essential to economical operation, their path is 75 determined and defined by baffle plates so disposed that the first pass or path followed by the gases in passing upwardly over the first or front bank of tubes is enlarged rearwardly to include sufficient of the space between the first and middle banks to accommodate the superheater. By this means the hot gases are forced to follow a path which includes practically the entire first bank of tubes, and so not come in contact with the 85 superheater, until after passing over such tubes. This arrangement has many advantages.

In the accompanying drawing Figure 1 is a cross section of a boiler equipped with a 90 superheater in the manner above described, and Fig. 2 is a sectional plan in the line x—x of Fig. 1.

The boiler specifically illustrated consists of three upper or steam drums A, B and C, 95 connected with a lower or water drum D by front, middle and rear banks of tubes designated by a, b, and c respectively, all located within the boiler heating chamber formed by the brickwork or setting E. These banks 100 of tubes are in series as regards the passage of the furnace gases, that is, the gases flow past the banks in succession and from end to end. The grate, not shown, is below the arched furnace top F. In the rear of the 105 middle bank b is a baffle plate g' extending downward from drum B, and in the rear of the first bank a is a baffle plate g, extending upwardly from the drum D to a point vertically beneath the rear header H of the 110 superheater S, from which point it extends upwardly to the said header or to the line

of contact between the header and the tubes of the middle bank *b*. The path for gases thus defined is extended upwardly to a point near the upper middle drum *B* by a second 5 baffle *g''* or by an extension of the baffle *g* in case the available space permits. In front of this baffle wall is placed the superheater *S*, which, as above stated, comprises a plurality of bent tubes connected to horizontal 10 transverse headers *H*, *H'*, which are, in turn, connected with the boiler and with the service steam main, respectively, in the usual way. As will be seen, the headers constitute the superheating supports, and are themselves supported by hangers *h* preferably 15 embedded in the brickwork of the setting and depending from I-beams *i*. These I-beams are those usually employed in connection with boilers of this type, and serve 20 to support the boiler, the drums of which rest in chairs *l* interposed between them and the drums. The beams *i* it will be understood form part of the usual frame, not shown, that is used with such boilers.

25 The special arrangement of baffle plates *g* and *g''* above described is not of the essence of the invention, the main feature of which is the enlargement by baffle walls of the front pass for the gases to include, in 30 addition to the front bank of tubes, a space sufficient to accommodate the superheater. This enlargement does not permit, at least to an appreciable extent, a diversion of the gases from the upper portions of the front 35 bank of tubes, as the line of draft is not substantially altered and the headers or other part of the superheater affords an obstacle in the more direct path for the gases along the baffle wall.

40 What I claim is:

1. The combination with a water-tube boiler having a plurality of banks of vertically extending tubes in series as regards the passage of the furnace gases, baffles between 45 the banks for defining the path followed by the gases in passing from one bank to the next, of a superheater comprising a plurality of headers and connecting superheater tubes, supported between the tubes of the front 50 bank and the upper portion of the baffle in the rear of the same, as set forth.

2. The combination with a water tube boiler having a plurality of banks of verti-

cally extending tubes in series as regards the passage of the furnace gases, separated by a 55 baffle over which the gases flow in passing from the front bank to the next, of a superheater comprising a plurality of headers connected by superheating tubes extending upwardly from the headers and supported between the tubes of the front bank and the upper portion of the baffle between the first and second banks, as set forth.

3. The combination with a water tube boiler having a plurality of banks of vertically extending tubes in series as regards the passage of the furnace gases, of baffles between the said banks of tubes for defining the paths followed by the gases, a superheater comprising headers connected by 60 superheating tubes extending upwardly from the headers and located between the first bank of tubes and the upper portion of the baffle between the first and second banks, and supports for said headers depending from 65 the means for supporting the boiler in the setting, as set forth.

4. The combination with a water tube boiler having a plurality of banks of vertically extending tubes in series as regards the passage of the furnace gases, of a baffle extending along the lower portion of the front bank of tubes immediately back of the same, and along the upper portion of the second bank of tubes immediately in front of the 75 same, and a superheater supported in the enlarged path for the gases formed by the upper part of said baffle, back of the first bank of tubes, as set forth.

5. The combination with a water-tube 80 boiler having a plurality of banks of vertically extending tubes in series as regards the passage of the furnace gases, baffles between the banks for defining the path followed by the gases in passing from one bank to the 85 next, of a superheater comprising a plurality of headers and connecting superheater tubes, supported between the tubes of the front bank and the baffle in the rear of the same, as set forth.

In testimony whereof I affix my signature in the presence of two subscribing witnesses.

100 ERNEST H. FOSTER.
